UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

VERTICAL COOLER.

Application filed April 26, 1926. Serial No. 104,675.

My invention relates to the canning art, and more particularly to an apparatus for cooling canned goods subsequent to the cooking thereof.

5 The principal object of my invention is to provide a simple and economical cooler, occupying comparatively little floor space in proportion to its capacity, and capable of operating upon a continuous and rapidly advancing procession of cans. Other objects are to provide for economy in the use of the cooling water, and to avoid submerging the cans therein, and a still further object is to provide means for positively and accurately 10 feeding the cans to the cooler and discharging them therefrom. These and other objects and advantages of the invention will be more fully set forth in the subsequent description of a preferred embodiment, which should be 15 read with the understanding that the form, construction and arrangement of the several parts may be varied, within the limits of the appended claims, without departing from the essential principles of the invention. It 20 should also be understood that my invention may be embodied in machines for purposes other than that described.

With this in view a preferred embodiment of my invention will now be fully described 25 with reference to the accompanying drawings, wherein—

Fig. 1 is a part sectional plan view of the complete cooler.

Fig. 2 is a broken vertical section, the 30 lower and upper portions thereof being taken on different radial planes to show, respectively, the feed and discharge mechanism illustrated in plan in Fig. 1.

Fig. 3 is a horizontal sectional detail, enlarged, of one of the reel bars.

Fig. 4 is a broken vertical section of the drive mechanism.

Fig. 5 is a vertical sectional detail of the upper portion of the cooling chamber and the propelling reel.

45 The body or shell of the machine comprises an annular chamber formed by concentric cylindrical walls 1 and 1' positioned about a vertical axis, and secured to a suitable base 2 as shown in Fig. 2. A cover plate 3, Figs. 1 and 2, extends over the entire shell. The inner shell cylinder 1' has secured to it, near its upper end, a spider 4, Fig. 5, spaced below the cover 3. A fixed central vertical 50 shaft 5 extends between said cover and said

spider, and serves as a bearing for a gear 6 of large diameter.

The annular cooling chamber formed by the cylindrical shell walls 1 and 1' is provided with a helical can path or track formed 60 by rails 7, Figs. 1 and 2, secured to said walls. The cans, as indicated at 8 in Fig. 1, are rolled along said track by a reel formed of spaced vertical bars 9 secured at their upper ends to the rim of the gear 6, as shown at 65 10 in Fig. 2. The lower ends of said bars are secured, at 11, to a ring 12, which lies in the lower portion of the annular cooling chamber and is guided by idler rollers, one of which is shown at 13, bearing against its 70 inner periphery.

The can propelling reel thus comprises the upper gear 6, the lower ring 12, and the series of spaced vertical pusher bars 9. Its weight is supported entirely by the bearing 75 of said gear 6 upon the shaft 5, a suitable thrust bearing 14 being provided at this point. In order to prevent distortion of the reel, it is driven from both ends, and for this purpose both the gear 6 and the ring 12 are 80 provided with peripheral teeth 15, Fig. 4, adapted for engagement by idler gears 16 which in turn are driven by pinions 17 secured upon a vertical shaft 18. The latter is driven in any convenient manner, as for example 85 by bevel gears 19, and a horizontal shaft 20 carrying a belt pulley 21.

The above described construction of the cooling chamber, can track, and reel, provides maximum rigidity and perfect alignment, thereby insuring free passage of the cans. The reel is insured against distortion by being driven from both top and bottom, and is held in accurate alignment by its top bearing upon the shaft 5 and its bottom 90 guide bearing upon the idler rollers 13, and the alignment of the can track is preserved by the mounting of its rails 7 directly and rigidly upon the chamber walls 1 and 1'. This construction also enables the entire 95 reel to be lifted out of the cooling chamber, for cleaning or repair, merely by the removal of the cover plate 3.

The reel bars 9 are preferably of channel section, as shown in Figs. 1 and 3, with their 105 open sides forward, to reduce the area of contact with the cans. In order to assist the cans in following the circular, or more properly, helical track, without excessive friction, the outer side 9' of each reel bar is 110

advanced slightly with respect to its inner side 9", as shown in Fig. 3, thereby causing the outer end of the can to lead its inner end sufficiently to cause it to follow the curved 5 track easily. This advancing or leading of the outer side 9' of the reel bar is best provided by mounting the entire bar at a slight angle to the true radial line. For convenience in manufacture, I prefer to weld the 10 ends of the bar to horizontal flange members 22, Fig. 2, which are bolted to the gear 6 and the ring 12 at 10 and 11 respectively. By off-setting said flange members with respect to the true radius, as shown in Fig. 3, the 15 desired angular lead of the bar is secured.

The cans are fed into the annular cooling chamber at the bottom of its helical track, and are discharged from its top, and during their helical upward progression, they are 20 subjected to a descending spray of cold water introduced at the top of the annular chamber, and discharged from its bottom. Thus the hot cans, when first introduced, come in contact with water which has been heated 25 by its passage over previous cans, and are gradually subjected to colder water as they approach the discharge at the top. By this arrangement I secure the most efficient exchange of heat.

30 It should be noted at this point that the cans are not submerged in water at any time. The water is introduced in the form of a spray, at the top of the annular cooling chamber, and trickles down over the helically ascending cans. The submerging of hot cans in cold water is not advisable in the canning art, for the reason that the sudden reduction in internal pressure in a can sometimes causes a small amount of water 35 to be sucked in through a seam, thereby introducing bacteria and spoiling the contents. Seams which will remain tight under all ordinary temperature changes may permit infinitesimal leaks when a hot can is suddenly plunged into cold water. By avoiding 40 submergence of the cans, and by cooling them gradually as described above, I eliminate this source of trouble.

The cooling water is preferably sprayed 45 into the top of the cooling chamber from a pipe 23, Fig. 5, provided with suitable outlet holes 24. This pipe lies within the cooling chamber throughout its entire circumference except where the cans are discharged. At 50 this point the pipe 23 is led outside the chamber, as shown in Fig. 1, and passes beneath the can discharge chute, as shown in Fig. 2. Any suitable outlet, not shown, may be provided for draining the water from the bottom 55 of the cooling chamber.

The cooling of the cans by means of a spray rather than a body of water has a further advantage in eliminating the necessity for a water tight cooling chamber. This 60 simplifies the construction of the can feeding

means and the lower reel bearings. The construction of an annular cooling chamber which is almost entirely filled with cans being treated results in considerable economy of water, because on account of the confined 70 space, all the water is brought into contact with the cans.

The close spacing of the reel bars 9 within the cooling chamber, and the horizontal position of the cans therebetween, makes it necessary to introduce and remove said cans through the side of the chamber, and in order to do this with the necessary speed and accuracy, and without damage to the cans, I provide the following mechanism.

The cans, on end, are supplied to the machine by any suitable conveyer represented in Fig. 1 by the track 25 and the chain or belt indicated at 26. A suitable timing device, preferably a worm 27, spaces the cans and feeds them in proper timed relation to a rotating turret or star wheel 28, by which they are advanced over an arcuate platform 29 provided with a peripheral guide rail 30, and fed into an opening 31 in the outer chamber wall 1, said opening being positioned just above the lower end of the helical can track formed by the rails 7, as shown in Fig. 2. The arcuate platform 29 terminates in an inclined portion 32, so that, as a can 95 approaches the opening 31, it is tipped over onto its side and falls upon the rails 7 within the cooling chamber. An arcuate guide rail 33 supported by a bracket 34, Figs. 1 and 2, assists the tipping of the can by engaging it near its top. The worm 27 and the star-wheel 28 are so timed, of course, as to feed the cans accurately into the spaces between the reel bars 7.

To insure such timing, I prefer to drive 105 the entire feed mechanism directly from the reel itself. For this purpose the star wheel shaft 35, Fig. 2, carries a gear 36, which is driven through idlers 37 from the gear teeth 15 of the bottom reel ring 12. The 110 shaft 35 drives, through bevel gears 38, a horizontal shaft 39 on which is mounted a suitable sprocket 40 for operating the conveyer 26 shown in Fig. 1. The timing worm 27 is driven from the horizontal shaft 39 115 by suitable gearing 41.

The cans are discharged through an opening 42, Figs. 1 and 2, in the upper portion 120 of the outer chamber wall 1, by means of a star wheel 43, which is driven by the engagement of the reel bars 9 with its projecting teeth, and which pushes the cans out, endwise, into a chute 44, down which they may roll by gravity. The curvature and position of the outer side wall 45 of said 125 chute is such that it engages the outer end of the can, as the latter is pushed out from between the reel bars 9 by the star wheel 43. This engagement, together with the continued pressure of the reel bar against 130

the inner end portion of the can, causes the can to swing sideways into a position which enables it immediately to roll away from the reel and down the chute 44.

5 I claim:—

1. In an apparatus for the described purpose, a helical track adapted for the rolling passage of a series of cans upon their sides; a propelling reel comprising a series of 10 spaced pusher bars disposed perpendicularly to the axes of the cans and adapted to engage the sides thereof; and means for feeding the cans onto said track and between said bars during the movement thereof, the 15 axes of said cans being maintained during said feeding in a plane radial to the axis of the reel.

2. In an apparatus for the described purpose, a helical track adapted for the rolling 20 passage of a series of cans upon their sides; a propelling reel comprising a series of spaced pusher bars disposed perpendicularly to the axes of the cans and adapted to engage the sides thereof; and means for feeding the cans onto said track and between said bars during the movement thereof by tilting said cans from their ends onto their sides.

3. In an apparatus for the described purpose, a can track adapted for the rolling 30 passage of a series of cans upon their sides; a series of spaced pusher members for advancing the cans along said track; and means for feeding the cans onto said track and between said pusher members during the movement thereof, said means comprising an inclined chute down which the cans are adapted to slide, on end, and by which they are tilted onto their sides upon said track.

40 4. In an apparatus for the described purpose, a can track adapted for the rolling passage of a series of cans upon their sides; a series of spaced pusher members for advancing the cans along said track; and means for feeding the cans onto said track and between said pusher members during the movement thereof, said means comprising an inclined chute down which the cans are adapted to slide, on end, and by which they are tilted onto their sides upon said track, 45 and means adapted to engage the upper end portions of the cans to assist the tilting thereof.

5. In an apparatus for the described purpose, a can track adapted for the rolling 55 passage of a series of cans upon their sides; a series of spaced pusher members for advancing the cans along said track; and means for removing the cans from said track 60 by pushing them endwise from between said members.

6. In an apparatus for the described purpose, a can track adapted for the rolling 65 passage of a series of cans upon their sides; a series of spaced pusher bars for advanc-

ing the cans along said track; and a movable member actuated by said bars for pushing the cans endwise from between said bars and off the track.

7. In an apparatus for the described purpose, 70 a can track adapted for the rolling passage of a series of cans upon their sides; a series of spaced pusher bars for advancing the cans along said track; means for pushing the cans endwise from between said bars; and a chute for receiving the cans from said member and conducting them away from the track.

8. In an apparatus for the described purpose, 80 a can track adapted for the rolling passage of a series of cans upon their sides; a series of spaced pusher bars for advancing the cans along said track; and means for removing the cans from said track by pushing them endwise from between said bars, turning them horizontally, and causing them to roll away from said track.

9. In an apparatus for the described purpose, 85 a helical track adapted for the rolling passage of a series of cans upon their sides; a propelling reel comprising a series of spaced pusher bars disposed perpendicularly to the axes of the cans and adapted to engage the sides thereof; and means for removing the cans from said track by pushing 90 them endwise from between said bars.

10. In an apparatus for the described purpose, 100 a substantially vertical cylindrical shell; a helical can track therein; a rotatable propelling reel comprising spaced substantially vertical pusher bars, a ring to which the lower ends of said bars are secured, and a member to which the upper ends of said bars are secured; idler rollers adapted to bear against said ring for guiding the lower end of said reel; bearing means associated with said member for supporting and guiding the upper end of the reel; and means for rotating said reel by engagement with both said ring and said member.

11. In an apparatus for the described purpose, 105 a substantially vertical cylindrical shell; a helical can track therein; a rotatable propelling reel comprising spaced substantially vertical pusher bars, a ring to which the lower ends of said bars are secured, and a member to which the upper ends of said bars are secured; idler rollers adapted to bear against said ring for guiding the lower end of said reel; and a central bearing for 110 said member to support and guide the upper end of said reel.

12. In an apparatus for the described purpose, 115 substantially vertical spaced concentric cylindrical shells forming an annular chamber; a helical can track within said chamber; a rotatable propelling reel comprising a series of substantially vertical spaced pusher bars, a ring to which the lower ends of said bars are secured, and a gear 120

to which the upper ends of said bars are secured; bearing means for said ring to guide the lower end of the reel; a fixed member secured within the upper end of the inner shell; a cover member secured to the top of the outer shell; a central shaft extending between said members and supported thereby, said shaft forming a bearing for said gear; and means for rotating the reel by engagement with said gear.

13. In an apparatus for the described pur-

pose, a cylindrical shell; a helical can track therein; a can propelling reel comprising end members and a series of spaced pusher bars having their ends secured thereto; bearing means for guiding both end members of said reel; and means for rotating said reel by engagement with both end members thereof.

In testimony whereof I have signed my 20 name to this specification.

ALBERT R. THOMPSON.
